UPPER ENGINE LUBRICATING DEVICE

Louis M. Herzfeld, Beverly Hills, Calif.

Application June 28, 1949, Serial No. 101,796

1 Claim. (Cl. 123—196)

1

This invention relates to an engine oiling device and more particularly to an oiling device for introducing lubricating oil into the upper end of the cylinders of an internal combustion engine.

It is an object of this invention to provide an engine lubricating device of the kind to be more particularly described hereinafter which is operable by the vacuum of the intake manifold or carburetor for introducing lubricating oil into the combustion mixture fed to the cylinders of an internal combustion engine to provide for the proper lubrication of the side walls of the cylinders in all the operating conditions of the engine.

Another object of this invention is to provide an upper engine lubricating device for injecting lubricating oil into the combustion mixture to lubricate the valve stems, bearings and seats, the gasoline mixer devices, the upper cylinder walls, upper piston rings and all other moving parts in the upper portion of the engine subject to excessive wear from the lack of proper lubrication when the engine is either extremely hot or extremely cold.

Still another object of this invention is to supply the engine lubricating oil to the parts in the cylinders in greater quantities when the engine is cold when the use of the gasoline choke, automatic or manual, washes away the thin film of lubricant generally provided. The supply of lubricant, while greater during the warm-up period, returns to the normal regulated amount after the engine has attained its operating temperature.

A further object of this invention is to provide a lubricating device or oiler of this kind which is continually maintained with an adequate supply of oil from the reserve supply in the oil pan of the engine. By providing a self-filling oiler of this kind the requirement for the manual, periodic, filling is eliminated and a constant supply of clean oil from the oil cleaner is always provided in the cylinders.

A still further object of this invention is to provide an oiling device of this kind which is responsive to both the speed and temperature requirements of the engine to provide the proper lubrication for the cylinders and is so connected to the combustion mixture control means to provide an added amount of air to be injected into the combustion charge after the engine is thoroughly warmed up to provide a more efficient and complete combustion of the charge resulting in a smaller carbon deposit.

2

With the above and other objects in view, my invention consists in the arrangement, combination and details of construction disclosed in the drawings and specification and then more particularly pointed out in the appended claim.

In the drawings:

Figure 1 is a side elevation, partly broken away, of an internal combustion engine, having an upper engine lubricating device constructed according to an embodiment of this invention.

Figure 2 is a side elevation of the engine lubricating device, removed from the engine.

Figure 3 is a top plan view of the lubricating device.

Figure 4 is a vertical section, taken on the line 4—4 of Figure 3.

Figure 5 is a transverse section, taken on the line 5—5 of Figure 2.

Figure 6 is a horizontal transverse section, taken on the line 6—6 of Figure 4.

Figure 7 is a transverse section, taken on the line 7—7 of Figure 2.

Figure 8 is a fragmentary transverse section, taken on the line 8—8 of Figure 4.

Referring to the drawings, the numeral 10 designates generally an internal combustion engine of the type generally used in automobiles and the like and the upper engine lubricating device 11 is designed for application to an internal combustion engine of this type to be connected between the carburetor or intake manifold thereof and the oil sump or pan. The engine 10 is formed with an oil sump 12 at the bottom thereof and generally an oil filter 14 is connected to the pump, not shown in the drawings, within the engine for cleaning the oil before it is pumped in a direction for lubricating the moving parts. A tube or line 15 is connected between the pump within the engine and the oil filter 14 and the discharge line, usually connected to the oil filter, is connected to the lubricating device 11, formed according to an embodiment of this invention.

While the engine lubricating device 11 is shown as connected to the oil filter 14, it is understood that the oil line which is connected to the lubricating device 11 may be connected at any other point in the lubricating system at which the oil of the engine may be pumped upwardly into the device. The lubricating device 11 is also shown in the drawings as connected to the carburetor 16, but it will be understood that the oil outlet port of the lubricating device 11 may be connected to either the carburetor 16 or to the intake manifold or at any other position along the

vacuum circuit or arrangement of the engine 10

which is operatively connected to the engine for introducing the combustion charge into the cylinders thereof.

The engine lubricating device 11 is formed of a short reservoir 17 having a top wall 19, a cylindrical side wall 18 and a bottom wall 20 which is threadably engaged in the lower open end of the wall 18. The wall 20 is formed with an aperture 21 therein within which an oil inlet fitting 22 is adapted to be threadably or removably engaged. A second aperture 24 is formed in the bottom wall 20 and an outlet fitting 25 is threadably engaged in the opening 24. A third aperture 26 is formed in the bottom wall 20 and a screw or plug 27 is threadably engaged in the threaded aperture 26 providing a drain plug in the opening 25 from which the lubricant contained within the reservoir 17 may be drained when it is desired to clean or service the lubricating device 11.

An upwardly extending tubular member or pipe 28 is fixed to or otherwise carried by the inlet fitting 22 and extends upwardly within the reservoir 17 approximately one-half the total length of the reservoir and the oil entering the reservoir is adapted to be entered through the inlet fitting 22 and pipe 28. The inlet fitting 22 is connected at its outer end to the pipe or line 30 which is connected at its other end to the discharge side of the oil filter 14.

An overflow pipe 31 is connected to the overflow fitting 25 and extends upwardly within the reservoir 17 for establishing a point, at its upper end, at which the oil or other lubricant within the reservoir 17 may be maintained. When the fluid entering the inlet pipe 28 has filled the container or reservoir 17 to the level of the upper end of the overflow pipe 31, the lubricant will flow downwardly through the pipe 31, the nipple 25 and the return line 32 which is connected at its upper end to the nipple 25 and at its lower end to the sump 12.

The reservoir 17, between the top wall 19, the bottom wall 20 and the side walls 18 define a lower oil supply chamber 34 for containing a supply of oil. A marginal bead or rib 36 is fixed to or formed on the upper side of the top wall 19 and a transparent, semi-cylindrical dome 37 is fixedly secured to the top wall 19 in engagement with the inner surface of the peripheral bead or flange 36 to form an upper or vacuum pressure chamber 35. A suitable sealing member 38 is adapted to be positioned between the extreme outer surface of the dome 37 at its lower end and between the inner surface of the flange 36 for sealingly securing the dome 37 on the reservoir 17, for the purposes to be hereinafter described.

The top wall 19 is formed with a passage or opening 39 therethrough which extends vertically, opening on the lower side thereof and at the upper end and a tube or pipe 40 is adapted to be positioned within the opening 39 and extended downwardly below the lower edge of the top wall 19 and upwardly within the chamber 35. The lower end of the oil line 40 is disposed adjacent the bottom wall 20 and will be substantially submerged within the oil supply contained within the reservoir, considerably below the upper constant level. The upper end of the tube 40 is arcuately bowed, as clearly noted in Figure 4 of the drawings, and opens downwardly within the chamber 35, the lower open end of the tube 40, within the chamber 35 being positioned upwardly in spaced relation the upper surface of

the top wall 19. The tube 40 is provided for conveying or conducting the lubricant from the lower chamber 34 upwardly into the upper chamber 35 as effected by the vacuum pressure in the manner to be described hereinafter.

A small well 41 is formed on the upper surface of the top wall 19 and positioned below the open end of the tube 40 within the chamber 35 and the top wall 19 is further formed with a passage 42 which opens at its upper end at the bottom of the well 41 and opens downwardly through the bottom surface of the top wall 19.

A vacuum line 44 is connected within the reservoir 17 for communication with the upper chamber 35 and is formed of a short length of tubing to be contained within the side walls 18. One end of the tube 44 is threadably engaged in the lower end of the passage 42 and the lower end of the tube 44 is connected to a nipple 45 on one side of the wall 18 for communication with an outside vacuum line. One end of the exterior vacuum line 46 is connected to the nipple 45 on the outside of the reservoir 17 and the other end of the vacuum line 46 may be connected to the carburetor 16 at a desired position, as at the throat, or the line 46 may be connected to the intake manifold of the engine 10. The normal operation of the engine 10 establishes a vacuum in the lines 46 and 44 and in the upper chamber 35. There being a vacuum in the chamber 35 and transfer line or pipe 40, the atmospheric pressure exerted on the surface of the fluid supply contained within the lower chamber 34 effects the movement of fluid upwardly through the pipe 40 into the upper chamber 34 and through the wall 41, passage 42 and vacuum lines 44 and 46 to be conveyed to the upper end of the cylinders of the engine, by way of the combustion charge within the intake manifold or carburetor.

A restricted vent passage or aperture 47 is formed in the flange 36 and is extended downwardly through the top wall 19 of the reservoir 17 for communicating the lower chamber 34 with the outside, atmospheric, air pressure. The aperture 47 provides for the entrance of air into the lower chamber 34 as the air is exhausted through the vacuum line during the operation of the engine 10.

For controlling the amount of fluid which will be transferred from the lower supply chamber 34 to the upper chamber 35, a needle valve 48 is threadably engaged in an outwardly extending threaded opening 49 formed in the top wall 19 and communicating at its inner end with the air conduit 55. The needle valve 48 is tensioned in a selected position as adjusted within the threaded aperture 48 by a coiled spring 50 which is engageable in a recess 51 which opens outwardly from the side wall of the reservoir 17, in the top wall 19 and bears against the inner surface of the head 52 on the outer end of the needle valve 48. The spring 50 supplies the suitable or desired tension for maintaining the needle valve 48 in its selected, adjusted position in the air conduit 55. The needle valve 48 is formed with a longitudinally extending bore or passage 54 which extends from the outer end thereof, in the head 52 to a transverse bore or passage 54' adjacent the extreme inner, pointed, end 55' of the needle valve. The passage 54 establishes communication from the outside atmospheric pressure with the upper chamber 35. A short air passage 55 opens at its lower end in communication with the air conduit 54 in the

needle valve 48. The portion of the hole 56, at the pointed end 55' of the valve 48 permits, by adjustment of valve 48, a large or small volume of air to be drawn into chamber 35, thus increasing or decreasing the vacuum therein, which, in turn, directly controls the flow of oil through the oil transfer line 40 to aperture 41.

A thermostat 57 is operatively connected to the lubricating device 11 and is connected to the vacuum means as represented by the passage 42 within the head or top wall 19. The thermostat 57 is formed of an elongated tubular body 58 having a cap or closure member 59 on the lower end thereof. A coupling member 60 is rotatably carried by the upper end of the tubular body 58 and is threadably engaged with a nipple or union 61 which is threadably engaged in a recess 62 on one side of the head 19, opposite from the adjusting screw 48. A bimetallic element 64 is fixed within the thermostat 57, by the fixed engagement of the upper end of the bimetallic element 64 within the tubular member 58 or thereabove, as shown in Figure 4 of the drawings, by connection with the downwardly extending passage 65 of the nipple or union 61. The cap 59 and lower end of the tubular body 58 are formed with a registering opening or air vent 66 extending outwardly therefrom. A needle or valve member 67 is carried by the extreme free lower end of the bimetallic element 64 and is adapted to be positioned in the aperture 66 for closing the air vent when the engine temperature is below the normal operating range. As the engine temperature rises, the bimetallic element 64 will be bowed for moving the valve element 67 out of closing engagement with the vent 66 to permit a certain amount of air to enter the lubricating device 11. The horizontal or inwardly extending passage 68 of the nipple or union 61 opens at its inner end in communication with a transverse, restricted air passage 69, formed in the top wall 19 between the oil passage 42 and the recess 62.

An L-shaped supporting bracket 70 is formed to be fixed at its lower end to the upper side of the engine 10 by the engagement of one of the head bolts or studs through the transverse or horizontal bar 71. The lubricating device 11 is fixedly supported on the vertically extending bar 72 by a fastening bolt 74 engaging through the side wall 18 of the reservoir 17 above the fluid level therein and through an aperture 75 in the upper end of the vertically extending bar or arm 72. The bolt 74 is fixed on the upwardly extending arm 72 by nuts 76 or other suitable fastening devices for fixedly securing the lubricating device on the bracket or supporting member 70. As the thermostat 57, carried by the lubricating device 11 is positioned in the drawings, substantially as a part of the reservoir 17, the thermostat will be positioned in close proximity to the head of the engine and is designed to be responsive to the temperature of the engine head. If it is desired to position the lubricating device 11 at some other place on the vehicle, remote from the engine, the thermostat 57 must be suitably positioned close to the engine to be responsive to the temperature thereof and the connection between the passage 66 and passage 69 of the head 19 may be accomplished by suitable tubing or other vacuum conveying means.

In the use and operation of the lubricating device 11, constructed according to an embodiment of this invention, the lubricating device is mounted on the bracket 70 immediately adjacent the upper end of the engine 10 and the thermo-

stat 57, fixedly carried by the reservoir 17 is positioned immediately above the head of the engine. The reservoir 17 is connected to the oil filter or oil pump by way of the oil line 30 for supplying oil to the reservoir and the constant level of oil within the reservoir is maintained by the overflow pipe 31 which conveys the excess lubricant downwardly out of the reservoir to the oil sump 12. When the engine is cold and not running, the bimetallic element 64 is swung to the left, as viewed in Figure 4 of the drawings whereupon the valve element 67 is engaged in the aperture 66 for closing the aperture. Upon initially starting the cold engine, the vacuum line 10 between the engine and the lubricating device 11 is established in the vacuum lines 46 and 44 for establishing a vacuum in the chamber 35. As the oil pump is operating at this time, or normally the level of the oil within the chamber 34 will be established prior to starting of the engine, the vacuum in the chamber 35 will draw the oil in the chamber 34 upwardly through the transfer tube 40 for flowing oil from the lower chamber 34 into the vacuum line 44 and thence to the manifold or carbureter 16. As the cold engine requires an excess of lubrication in the upper end of the cylinders, the closing of the aperture 66 provides for the full application of the vacuum for drawing oil upwardly out of the reservoir 17. As the engine temperature rises, the bimetallic element 64 will move the valve element 67 out of the aperture 66 thereby relieving the vacuum pressure as exerted within the chamber 35 for lifting the oil from the lower chamber 34. During the operation of the engine the thermostat 57, being responsive to the temperature of the engine, will suitably control the transfer of the oil from the reservoir 17 into the intake manifold or intake line to the upper end of the cylinders. By adjusting the set screw 48, the maximum, initial, transfer of oil from the lower chamber 34 to the cylinder heads may be suitably controlled, the adjustment of the set screw 48 determining only the maximum flow of lubricant to the engine from the lubricating device 11 while the thermostat 57 will suitably control the transfer of oil as the engine temperature rises to operating condition. After initially setting the set screw 48, no further attention need be given to the initial or maximum setting as the thermostat 57 will suitably control the oil transfer. The control of the thermostat 57 will normally provide for the variation of the oil transfer from six drops of oil per minute from the lower chamber 34 to the vacuum line 46 to a maximum of twelve drops a minute when the engine is cold. The normal range of engine temperature is from 60° F. to 140° F. and the thermostat controlled valve opening 66, together with the valve element 67 are formed for providing the range of oil transfer from six to twelve drops within the normal temperature range.

I do not mean to confine myself to the exact details of construction herein disclosed, but claim all variations falling within the purview of the appended claim.

I claim:

In a lubricating device for an internal combustion engine, a lubricant reservoir having a top wall closing the same, a dome mounted on the top wall and forming therewith a vacuum pressure chamber, supply means for said reservoir, an overflow pipe in said reservoir for maintaining a constant level of lubricant, a pipe extending through the top wall and connecting the

chamber and the reservoir, a passage in said top wall communicating at one end with said chamber, a vacuum line from the intake manifold of the engine connected to said passage at the other end thereof, a tubular body supported at one end in said top wall, said body communicating at said one end with said passage, said body having an opening therein for connecting the interior of said body with the atmosphere, a valve in said tubular body for closing said opening, a bimetallic thermostat connected to said valve, said valve being operable by the thermostat in response to the engine temperature for controlling the extent of communication of the passage and chamber with atmospheric pressure.

LOUIS M. HERZFELD.
